ERNST RUHMER, OF BERLIN, GERMANY.

MULTIPLE TELEPHONY.

Specification of Letters Patent. Patented Oct. 19, 1920.

1,356,222.

Application filed April 4, 1911, Serial No. 618,871. Renewed February 4, 1919. Serial No. 275,001.

To all whom it may concern:

Be it known that I, ERNST RUHMER, engineer, a subject of the German Emperor, residing at Berlin, 248 Friedrichstrasse, in the Empire of Germany, have invented new and useful Improvements in or Relating to Multiple Telephony, for which application has been made in France April 5, 1910.

This invention relates to a method by means of which it is possible to transmit simultaneously several telephonic messages by one and the same wire.

For transmitting conversations, as in wireless telephony by means of electric waves, alternating currents of high frequency and of different frequency are used which are superposed on the line and are separated only at the receiving station where they act on different oscillatory circuits tuned with corresponding oscillatory transmission circuits communicating with the receiving apparatus.

In this method a comparatively loose coupling is used for connecting the transmission line to the different receiving circuits, as well as the latter to each other, for the purpose of obtaining a perfect separation of the different conversations and thus for avoiding any possibility of hearing unintentionally even the strongest of the latter, which, more particularly in a case of a large number of simultaneous transmissions, might have a very awkward effect.

Several arrangements according to this invention are illustrated by way of example in the accompanying drawings.

In the drawing,

Figure 1 is a diagrammatic view representing the transmitting and receiving stations with independent sources of high frequency currents at each transmitting station.

Fig. 2 represents diagrammatically a modified form of my improved system.

Fig. 3 shows a combined sending and receiving station embodying my invention.

In Fig. 1, $A^1 B^1 C^1 A^2 B^2 C^2$ are respectively the corresponding transmitting and receiving stations.

In order to produce high frequency currents, a known high frequency generator is used here, for instance, a generator of electric waves comprising an electric arc g with an oscillating circuit c l placed in parallel.

The different oscillatory circuits are ad-

justed to different numbers of oscillations by a suitable choice of the capacity c and of the self-induction l .

The intensity of the high frequency currents produced in these circuits is influenced by talking microphones m , which in some cases are in series with batteries b , b' , b'' , b or b' respectively. Either the supply current, or the high frequency current of the oscillatory circuit can be affected at will.

A change in the coupling between the emission circuit and the line, is equivalent to a change of intensity of the high frequency current passing through the circuits.

Generally speaking, any methods can be used, provided that the microphone of a certain emitting station cannot affect the alternating currents passing into the common line and emitted by other stations. There are receiving installations corresponding to the emission stations thus arranged.

In the drawing $A^2 B^2$ are oscillatory circuits tuned to the periods of the oscillatory circuits of the corresponding emission stations $A^1 B^1$. They act on the different receiving telephones t owing to the insertion of a detector d , as in wireless telephony with electric waves. At C^2 , the transformation is effected direct, without a detector, by means of a telephone w with Foucault currents.

The transmission of different talking currents is effected by the common line which can have a comparatively tight coupling to the transmitting oscillatory circuits, but on the contrary, as already stated, must be coupled comparatively loosely to the receiving circuits.

Fig. 2 shows a simplified installation which does not require special apparatus for producing high frequency current.

By talking into the microphone m , there is produced in the oscillatory circuit constituted by the capacity c and the self-inductance l , trains of damped waves corresponding to the sound waves acting on the microphone.

All that has been said with reference to Fig. 1, is also applicable in this case.

Fig. 3 shows a further improvement. It relates to an arrangement by means of which it is possible to use the same oscillatory circuit at one time as a transmitter,

and another time as a receiver, so that it is possible alternately to talk and to listen with one and the same apparatus. This result is obtained owing to a commutator or switch *s* which switches into the oscillatory circuit, either the microphone *m* and the battery, or the detector *d* and the telephone *t*.

This switch can be designed so as to allow at the same time of a change of coupling of the self-induction coil *l* with the line *f*, so that when talking, there is produced a tighter coupling, and when listening, a looser coupling. This is effected by connecting switch *s* by means of rod *r* with one arm of bell crank or bent lever *g*, and connecting the other arm of *g* by means of rod *r'* with pivoted arm *s'*, to which is attached coil *l*.

Having now particularly described and ascertained the nature of my said invention and in what manner the same is to be performed, I declare that what I claim is:

1. In a system of multiplex telephony, a plurality of stations having both transmitting and receiving apparatus, a common line circuit, means coupled to said line circuit for impressing electric oscillations of different frequencies upon said line circuit, means for modifying said electric oscillations by sound waves, local circuits at each station tuned to a particular frequency of said electric oscillations and means for placing either the transmitting or the receiving apparatus in operative connection with the common line circuit, and for simultaneously changing the coupling between said local circuits and the common line circuit.

2. The combination with a conductor, of transmission means coupled thereto for impressing electric oscillations thereon, receiving means associated with said transmission means, and shifting means operative to place either said transmission means or said receiving means into operative relation to said conductor and to simultaneously modify the coupling between said conductor and said transmission means.

3. The combination with a conductor provided with a coil, of a coil inductively related to and movable with respect to said first mentioned coil, transmission means for impressing electric oscillations on said second mentioned coil, receiving means for re-

ceiving electric oscillations from said second mentioned coil, and means operative to connect either said transmission means or said receiving means operatively to said second mentioned coil and to vary the distance between said coils as a result of such connection.

4. The combination with a conductor provided with a coil, of a coil inductively related to and movable with respect to said first mentioned coil, transmission means including a microphone for impressing electric oscillations on said second mentioned coil, receiving means including a telephone and a detector for receiving electric oscillations from said second mentioned coil, and means operative to connect either said transmission means or said receiving means operatively to said second mentioned coil and to vary the distance between said coils as a result of such connection.

5. The combination with a conductor, of means spaced from but inductively connected to said conductor, transmission means for impressing electric oscillations on said first mentioned means, receiving means for receiving electric oscillations from said first mentioned means, and means operative to connect either said transmission means or said receiving means operatively to said first mentioned means and to simultaneously and automatically vary the distance between said conductor and said first mentioned means.

6. The combination with a conductor, of means spaced from but inductively connected to said conductor, transmission means for impressing electric oscillations on said first mentioned means, receiving means for receiving electric oscillations from said first mentioned means, and switching means operative to connect either said transmission means or said receiving means operatively to said first mentioned means and to simultaneously and automatically vary the distance between said conductor and said first mentioned means.

In testimony whereof I affix my signature in presence of two witnesses.

ERNST RUHMER.
